UNITED STATES PATENT OFFICE.

FRANK R. HAHN, OF DECATUR, ILLINOIS, ASSIGNOR OF ONE-HALF TO W. P. LANDON,
OF ROCHELLE, ILLINOIS.

SEPTIC TANK AND LIKE CONSTRUCTION.

Application filed September 12, 1924. Serial No. 737,262.

To all whom it may concern:

Be it known that I, FRANK R. HAHN, a citizen of the United States, a resident of Decatur, in the county of Macon and State 5 of Illinois, have invented certain new and useful Improvements in Septic Tanks and like Construction, of which the following is a specification.

This invention relates to improvements 10 in septic tanks and like constructions and has for its object the provision of such construction composed of a plurality of units or elements a number of which are interchangeable and all of which are of standard 15 construction, and which may be molded or cast separately and then assembled together at the place where it is desired to install the tank. If conditions permit the erection and installation of the tank in the cavity which 20 the tank is to be located this may be done or if it is necessary to assemble the tank and then move and lower the same into position this may be done.

Another object of the invention is the 25 provision of such a construction which includes means for assembling and securely locking and holding the various units and elements in position and in such a way as to prevent leakage.

Another object of this invention is the 30 provision of such a construction which may be used in the form of a single tank or compartment or which may be arranged in the form of a plurality of tanks or compartments and these latter may be arranged 35 side by side or end to end.

Further objects of this invention include 35 improvements in details of construction and arrangement whereby a simple strong and 40 efficient structure of the type described is provided which may be readily erected and installed at a minimum expense and supervision and which complies with the various laws and regulations in respect to structures 45 of this character.

To the accomplishment of the foregoing and such other objects as may hereinafter appear, this invention consists in the construction, combination and arrangement of

parts hereinafter described and then sought 50 to be defined in the appended claims, reference being had to the accompanying drawings forming a part hereof and which show merely for the purpose of illustrative disclosure, various embodiments of this invention, it being expressly understood however, 55 that various changes may be made in practice within the scope of the claims without digressing from my inventive idea.

In the drawings:

Figure 1 is a vertical cross section 60 through a device constructed to embody my invention.

Figure 2 is a perspective of a plurality 65 of the side and longitudinal units or elements assembled together.

Figure 3 is a perspective view of a plurality 70 of the end elements or units assembled together.

Figure 4 is a side elevation partially in 75 section of one of the units or elements showing the interior structure.

Figure 5 is a side elevation of one form 80 of a baffle board.

Figure 6 is a horizontal cross section 75 through a corner of the structure to show the details of that construction.

Figure 7 is a front elevational view of 85 the corner unit or elements.

Figure 8 is an end elevation of the same. 80

Figure 9 is a detailed view of the bonding member used in the corner construction.

Figure 10 is a view and side elevation of 85 a modified form of end unit or element.

Figure 11 is a side elevation of a modified 85 form of side or longitudinal unit or element, this form being made in two parts.

Figure 12 is a detailed cross sectional 90 view showing one form of foundation.

Figure 13 is a diagrammatic view showing 90 one method of arranging a construction of this character which includes a plurality of tanks or compartments arranged end to end.

Figure 14 is a diagrammatic view of another 95 form of this construction showing a plurality of tanks or compartments arranged side by side.

Figure 15 is a side elevation of a plurality of end units or elements assembled together to form the construction shown in Figure 14.

5 Figures 16 and 17 are perspective views of the slightly modified form of corner construction.

10 Figure 18 is a perspective view of tank constructed to embody my invention composed of units of this modified construction.

15 Figure 19 is a top view of the tank of this character showing a drip cap used when the device is to be used for a stock tank.

20 Figure 20 is a detailed enlarged perspective of one of the drip cap elements.

25 Referring now to the drawing and first to Figures 1 to 4 inclusive the numeral 1 indicates a standard and simple form of septic tank embodying this invention shown 30 assembled and installed in position. As shown, it is of substantially rectangular shape and its longer dimension is in the direction of travel of the material through the tank. The tank itself is formed of a 35 plurality of side or longitudinal units or elements 2 and a plurality of end elements or units 3. These elements or units 2 and 3 are shown in detail in Figures 2, 3 and 4 of the drawing. Each one is in the form 40 of a elongated slab having a rib or bead 4 along one edge thereof and a groove or recess 5 along the other edge thereof adapted to fit the rib or bead 4 in the next adjacent unit. By this construction the parts inter- 45 fit and are interlocked. The ends of each of the side or longitudinal units or elements 2 is formed with a cut-away portion 6 leaving a shouldered extension 7, whereas each end of the end units or elements 3 is formed 50 with a cut-away portion 8, leaving a shouldered extension 9, these last mentioned parts being oppositely arranged to the cut-away portion 6 and shouldered extension 7 of the side or longitudinal members whereby the 55 shouldered extensions 7 fit within the cut-away portions 8 of the end units or elements 3 and the shouldered extensions 9 thereof fit within the cut-away portions 6 of the longitudinal units or elements in the form of 60 a mortise and tenon construction. This will be readily apparent from a consideration of Figures 2 and 3 particularly. In each of the shouldered extensions 7 of said longitudinal members 2 is provided a socket 65 member 10 which is in the form of a metallic sleeve of two or more internal diameters, as indicated particularly in Figure 4 of the drawing and forms a vertical passage therethrough having the reduced part 11 and the enlarged part 12 with a shoulder 13 at their junction. Each of the end units or elements 3 has a similar socket member 14 provided in the shouldered extension 9 thereof, this socket member being in the 65 form of a metallic sleeve having parts of

70 different internal diameters, as at 15 and 16, the last mentioned part 16 being adapted to register with and fit into the larger portion 12 of sleeve 10 and the end thereof may or may not rest upon the shoulder 13 of sleeve 10. This construction results in proper alignment of the various units when they are assembled and also provides a bore or 75 passage extending entirely through the corner of the structure as a whole which is adapted to receive a suitable securing means to be presently described.

75 Referring again to Figure 4 of the drawing, each of the units or elements 2 and 3 is provided with suitable reinforcing means 80 as illustrated including one longitudinally extending member 17 and another longitudinally extending member 18. The latter has each end formed with an eye or opening 19 to receive and to embrace the sleeve 10 whereby the latter is securely held in position within the unit or element.

85 When installing a construction of this kind, suitable stringers or beams 20 are provided, see Figure 12. These stringers or beams 20 are elongated in form having a sloping upper surface 21 and a straight or level lower surface 22. The upper surface 21 is bounded at one end by the shoulder or abutment 23 and at the other end by the shoulder or abutment 24. Each stringer or beam member 20 is also provided with an aperture 25 therethrough near each end which leads to a socket or recess 26 having a suitable nut or other threaded member 27 90 therein. A plurality of these stringers or beams 20 are provided, as necessary and they are suitably spaced apart. If necessary are supported on the foundation members or piles 28, see Figure 12, which may be of 95 any size, shape or construction, according to the conditions encountered. These last mentioned members 28 may be provided with a recess or socket 29 having a suitable nut or other securing means 30 located in 100 the bottom thereof.

105 The floor of the construction is formed of a plurality of slabs or units 31 which are provided with a tongue and groove construction 32 so as to inter-fit and inter-lock. 115 They are placed upon the sloping surfaces 21 of the stringers or beams 20 whereby a sloping floor is provided. The end members of the series of floor boards engage the shoulders 23 and 24 of the beams or stringers 120 20 and are thereby held against sliding movement on the foundation of the structure. The units or the walls of the structure are formed by mounting a plurality of 125 said units or elements 2 and 3 on top of said floor members, as illustrated in Figures 1, 2 and 3. The lowermost of the longitudinal members is formed with a sloping lower edge 2' so as to fit the sloping surface of the floor, the remainder of the longitudinal 130

members being straight and level in construction. The securing means for each corner is in the form of an elongated rod or shaft 33 which passes through the aligned bores of the sleeves 10 and 14 and is provided with a threaded extremity which is screwed into the nut or other securing means 26 or 30, as the case may be. This construction results in securely locking and holding the parts and structure in position on its foundation.

To assist in maintaining stability and security, I provide a novel form of corner construction which includes the corner element or unit 34, see Figures 6, 7 and 8. This is in the form of a elongated slab having beveled side edges 35 which fit against the inner surfaces of the end and side walls of the construction at the corner thereof. This corner unit or element 34 is also provided with a longitudinally extending reinforcement 36 and a plurality of openings 37 therethrough to expose the reinforcement 36 at intervals. These openings are preferably arranged so as to be near the joints between the units or elements 2 and 3 of which the construction is formed. A bonding member 38, see Figure 9, is adapted to be looped around the exposed portion of the reinforcement and has its ends 39 flattened and apertured as at 40, so as to fit within the joint of the adjacent units or elements, the apertures 40 being for the purpose of permitting the passage of the securing rod or shaft 33 therethrough as well as the extended portions of the sleeve 10 or 14. After these corner units or elements are assembled in position the space between the corner element and the side and end walls may be filled with suitable cement or plastic material whereby a secure and permanent construction is formed.

The top of the construction is formed of a plurality of units or elements 41 which preferably have the tongue and groove construction 42 and the end members of which are provided with a tongue or groove 43 to fit the complementary part on the upper-most side and end members forming the side and end walls of the construction. Certain of these top members are provided with openings 44 communicating with upwardly extending tile connections 45 which lead to the top of the ground for purposes of observation and for entrance into the construction after installation. The intermediate top members are of special construction and two of them, designated 41¹, have a single beveled edge 41², while a third one designated 41³ is formed with the beveled edges 41⁴ to fit the correspondingly beveled edges 41² of adjacent members 41¹. This results in a tight fit as well as in a wedging action to hold the various parts together.

The upper members forming the end walls

are provided with suitable openings or apertures 46 to receive the inlet and outlet pipes 47. The upper members 2 of the side walls are provided with openings or recesses 48 near each end thereof to receive a baffle board 49, see Figures 1 and 5. This baffle board is in the form of an elongated unit having a shouldered extension 50 at each end adapted to fit within one of said recesses or sockets 48 and having a longitudinal reinforcement 51 extending therethrough. The ends 52 thereof are turned downwardly and extend without the shoulder, as at 53, to form a securing means which is adapted to fit within a suitable socket or recess formed in the upper-most side unit or element 2 and in the aperture or recess 48 therein.

In order to comply with certain requirements or regulations, it is necessary on occasion to provide a catch basin and I illustrate such a construction in Figure 1, where the catch basin is designated generally by the reference numeral 54. It is in the form of a cylinder 55 having one end closed and having its open end formed with an annular shoulder 56 adapted to fit in a correspondingly shouldered recess 57 formed in the bottom or floor members 31. Within this member 55 I provide a removable cylindrical receptacle 58. This forms a very important feature of this construction especially under certain working conditions.

In the event the side members 2 are of too heavy construction due to the dimensions thereof, they may be formed in two or more parts and the end members correspondingly changed. I illustrate these modifications in Figures 10 and 11, the numeral 59 designating the end member having the inlet or outlet opening 60 formed therein and provided with an intermediate shouldered extension 61 at each end which is provided with a sleeve 62 therein, said sleeve having portions of different diameters the smaller portion 63 extending beyond the lower edge of the shouldered extension 61. In Figure 11, the numerals 64 and 64' designate the complementary parts of one of the side or longitudinal members corresponding to the members 2 of the simpler form, these members 64 and 64' are formed so as to complement each other and to that end have the complementary sockets or recesses 65 for receiving and supporting the baffle board 49. Each of the members 64 and 64' is also provided with a shouldered extension 66 having the sleeve 67 therein formed of a plurality of diameters with the smaller portion of the sleeve 68 extending below the lower edge of the shoulder so as to fit within the larger diameter of the adjacent sleeve 62 or 67, as the case may be.

It may be necessary or desirable in providing installations or constructions for larger uses to make provision for a plural-

ity of tanks or compartments and I show two methods of making such provision. In the one shown in Figure 13, the tanks or compartments are arranged end to end and 5 inter-communicate one with the other so that the material passes through the entire series of tanks or compartments during the course of its treatment, whereas in Figure 14 the tanks or compartments are arranged 10 side by side and the material being treated only passes through one tank. It is understood that in this latter form connections may be made to either tank or compartment as desired. These installations are 15 constructed in substantially the same way as the construction previously described and the same reference characters are applied thereto to indicate the corresponding parts and a detailed description of them and of 20 their construction is not believed to be necessary. In Figure 13, 69 designates the inlet into end compartment 70 which has the pipe 71 communicating to the intermediate tank or compartment 72, which also has pipe 25 73 communicating to the end tank or compartment 74 which has the discharge or outlet connection 75. In this end tank or compartment is provided a settling basin construction 76 and baffle boards 77 may be utilized where desirable or necessary. In 30 Figure 14, 78 designates the inlets and 79 the outlets and 80 the baffle boards which are arranged out of line on account of the positions of the supporting slots or sockets 35 therefor.

In building these multiple constructions, a slight change in the formation of the side and end units or elements is necessary and this construction is shown in detail in Figure 40 15 of the drawing. This unit or element is designated generally by the reference character 81, and it is provided with the cut-away portion 82 leaving the shouldered extension 83. In certain of these 45 units this shouldered extension is referred to as 83' as it is longer than the usual shouldered extension 83, so that when the units 50 are assembled, a space 84 is left at intervals to receive the shouldered extension of the partition forming unit or element which is of substantially the same construction, as the units or elements 81. The enlarged shouldered extensions 83' are provided with the aperture or bore 85 to register with the aperture or bore 86 through the other shouldered extension 83, and said shouldered extension 83' is also provided with a socket or recess 87 to receive a depending member or part of the reinforcement, as shown in 60 the baffle board construction of Figure 5, whereby such units or elements which form the partitions are securely held in proper position.

I show in Figures 16, 17 and 18 a modified

form of corner construction. The units 2' 65 and 3' are formed with the enlarged shouldered end portions 90 and 91 having the same interlocking sleeve constructions 11 and 12 previously described.

This tank construction is also adapted for 70 use as a stock tank or the like and in that event I utilize a drip cap or top rim construction shown in detail in Figures 19 and 20. This construction includes a plurality 75 of elongated units 92 which have the rounded top surface 93 and the grooved under surface 94 to fit over and engage the top edge of the units 2 and 3 of the tank. The under surfaces of these units are formed on a bevel as at 95. The ends of each unit are 80 cut out as at 96 to expose the loops 97 to the reinforcing means 98, whereby the adjacent loops may be interlocked or fastened together by suitable securing means 99 as shown. 85

In constructing, assembling and installing structures of this character, it is to be understood that suitable waterproofing means is to be utilized between the various joints and openings and that the inside 90 faces or surfaces of the structure may be water-proofed in any suitable and desirable way.

These structures may be assembled and built in position in the cavity or if working conditions render that impossible, may be constructed and assembled above the water line and lowered in assembled condition on to the proper foundation. 95

The manufacture and making of the various parts of this structure is a comparatively simple and inexpensive matter and the structures are of standard design and may be readily and quickly assembled and installed in proper position at a very reasonable expense both in time and in money. The parts are all securely connected and locked together whereby a rigid, stable and permanent structure of this character is provided. 100 105 110 115

I claim:

1. A construction of the character described including in combination a foundation having a plurality of stringers or beams, having sloping upper surfaces, a floor mounted on said sloping upper surfaces, side and end walls each composed of a plurality of units or elements arranged on said floor and a top or cover member composed of a plurality of units or elements positioned on said side and end walls, said end walls having inner and outer connections. 120 125

2. A construction of the character described including in combination a foundation having a plurality of stringers or beams, having sloping upper surfaces, a floor mounted on said sloping upper surfaces, side and end walls each composed of

1. A plurality of units or elements arranged on said floor, a top or cover member composed of a plurality of units or elements positioned on said side and end walls, said end walls having inner and outer connections and a plurality of baffle boards mounted between and connected to said side walls. 65
2. A construction of the character described including in combination a foundation having a plurality of stringers or beams, having sloping upper surfaces, a floor mounted on said sloping upper surfaces, side and end walls each composed of a plurality of units or elements arranged on said floor, a top or cover member composed of a plurality of units or elements positioned on said side and end walls, said end walls having inner and outer connections, one of the units or elements of the top or cover member being formed with beveled side edges so as to have a wedging or forcing action when placed in position. 70
3. A construction of the character described including in combination a foundation having a plurality of stringers or beams, having sloping upper surfaces, a floor mounted on said sloping upper surfaces, side and end walls each composed of a plurality of units or elements arranged on said floor and a top or cover member composed of a plurality of units or elements positioned on said side and end walls, said end walls having inner and outer connections, said side and end units or elements each having a shouldered extension having an opening therethrough adapted to register with a complementary shouldered extension of the adjoining member and securing means passing through said aligned openings. 75
4. A construction of the character described including in combination a foundation having a plurality of stringers or beams, having sloping upper surfaces, a floor mounted on said sloping upper surfaces, side and end walls each composed of a plurality of units or elements arranged on said floor and a top or cover member composed of a plurality of units or elements positioned on said side and end walls, said end walls having inner and outer connections, said side and end units or elements each having a shouldered extension provided with an opening therethrough and adapted to interfit with a complementary shouldered extension on the adjoining interior element so as to align openings and securing means passing through said aligned openings. 80
5. A construction of the character described including in combination a foundation having a plurality of stringers or beams, having sloping upper surfaces, a floor mounted on said sloping upper surfaces, side and end walls each composed of a plurality of units or elements arranged on said floor and a top or cover member composed of a plurality of units or elements positioned on said side and end walls, said end walls having inner and outer connections and a catch basin provided near the lowermost point of the sloping floor. 85
6. A construction of the character described including in combination a foundation having a plurality of stringers or beams, having sloping upper surfaces, a floor mounted on said sloping upper surfaces, side and end walls each composed of a plurality of units or elements arranged on said floor and a top or cover member composed of a plurality of units or elements positioned on said side and end walls, said end walls having inner and outer connections and a 90
7. A construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension on the adjoining interior element so as to align openings and securing means passing through said aligned openings. 95
8. A construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension on the adjoining interior element so as to align openings and securing means passing through said aligned openings, sleeve members installed in said openings, said sleeve members being of different internal diameters and having a smaller portion extending beyond the edge of the interior element so as to fit within the enlarged portion of the adjacent sleeve. 100
9. A construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension on the adjoining interior element so as to align openings and securing means passing through said aligned openings, inner and outer openings provided near the top of the end walls, a plurality of openings provided near the top of the side walls and baffle boards having reduced shouldered extensions adapted to fit within said openings in said side walls 105
10. A construction of the character described including in combination a foundation member, a floor member, side and end walls each composed of units or elements and a top or cover member, said units or elements being of tongue and groove construction whereby they interfit with each 110
11. A construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension on the adjoining interior element so as to align openings and securing means passing through said aligned openings, inner and outer openings provided near the top of the end walls, a plurality of openings provided near the top of the side walls and baffle boards having reduced shouldered extensions adapted to fit within said openings in said side walls 115
12. A construction of the character described including in combination a foundation member, a floor member, side and end walls each composed of units or elements and a top or cover member, said units or elements being of tongue and groove construction whereby they interfit with each 120
13. A construction of the character described including in combination a foundation member, a floor member, side and end walls each composed of units or elements and a top or cover member, said units or elements being of tongue and groove construction whereby they interfit with each 125

- other, each unit or element having a provided in said unit or element and having an eye at each end to embrace said sleeve.
5. In a construction of the character described, a unit or element formed of plastic material cast in elongated rectangular shape and having a reduced shouldered extension 50 at each end provided with an opening therethrough, a sleeve fitting each opening, longitudinally extending reinforcing member provided in said unit or element and having an eye at each end to embrace said 55 sleeve, said sleeve having parts of different internal diameters with the smaller part extending beyond the edge of said unit or element.
10. In a construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension 60 on the adjoining interior element so as to align openings and securing means passing through said aligned openings, corner units or elements provided in each corner of the structure having a plurality of 65 engaging means exposed along its length and bonding members adapted to connect said engaging means with said securing means.
15. A construction of the character described including in combination a foundation member, a floor member, side and end walls each composed of units or elements and a top or cover member, said units or elements being of tongue and groove construction whereby they interfit with each other, each unit or element having a shouldered extension provided with an opening therethrough and adapted to interfit with a complementary shouldered extension 70 on the adjoining interior element so as to align openings and securing means passing through said aligned openings, corner units or elements provided in each corner of the structure having a plurality of 75 engaging means exposed along its length and bonding members adapted to connect said engaging means with said securing means, said bonding members having flattened apertured ends to fit within the joints 80 between the end and side units or elements and to receive said securing means.
20. In a construction of the character described, a unit or element formed of plastic material cast in elongated rectangular shape and having a reduced shouldered extension 85 at each end provided with an opening therethrough, a sleeve fitting each opening, longitudinally extending reinforcing member
25. In a construction of the character described, a baffle board unit or element formed of plastic material and cast in general elongated rectangular form having reduced shouldered extensions at each end and having positioning and holding means projecting downwardly from said reduced shouldered extensions.
30. In a construction of the character described, a baffle board unit or element formed of plastic material and cast in general elongated rectangular form, having reduced shouldered extensions at each end and having positioning and holding means projecting downwardly from said reduced shouldered extensions, said last mentioned 70 means being provided by a longitudinal reinforcing member which extends entirely through said baffle board unit or element, having portions located within said shouldered extension with the free ends projecting beyond the same.
35. In testimony that I claim the foregoing, I have hereunto set my hand this 28th day of April, 1924.

FRANK R. HAHN.
